UNITED STATES PATENT OFFICE.

HUMPHREY O'SULLIVAN, OF LOWELL, MASSACHUSETTS.

DESIGN FOR A HEEL.

SPECIFICATION forming part of Design No. 31,382, dated August 8, 1899.

Application filed July 12, 1899. Serial No. 723,617. Term of patent 14 years.

To all whom it may concern:

Be it known that I, HUMPHREY O'SULLIVAN, a citizen of the United States, residing at Lowell, in the county of Middlesex and State of Massachusetts, have invented and produced a certain new and original Design for a Heel; and I do hereby declare the following to be a full, clear, and exact description of the invention, such as will enable others skilled in the art to which it appertains to make and use the same.

The accompanying drawing is a perspective view of the heel.

As shown in the drawing, the leading and material feature of my design consists of a heel-shaped body provided with five substantially hemispherical-shaped projections on one side thereof arranged one near each cor-

ner, a third located equidistant from the other two just referred to and near the rear of the body, and two others located, respectively, near the edges of the body and equidistant from the ones at the corners and the one at the rear.

Having thus described my invention, I claim as new and desire to secure by Letters Patent—

The design for a heel substantially as shown and described.

In testimony whereof I affix my signature in presence of two witnesses.

HUMPHREY O'SULLIVAN.

Witnesses:

HORACE VAN EVEREN,
T. HART ANDERSON.
